Filed July 27, 1964, Ser. No. 81,020

Term of patent 14 years

(Cl. D9—2)

FIG. 2

FIG. 3

FIGURE 1 is a perspective view showing the front and one side of a vacuum and blower unit for cleaning a textile machine showing my new design;

FIGURE 2 is a perspective view of the rear and opposite sides thereof; and

FIGURE 3 is a top plan view of the vacuum and blower unit.

The rear and side of the base portion immediately below the hood of the disclosed vacuum and blower unit, not shown, are substantially the same in appearance as the front and side shown, except as indicated.

The broken line showing of the textile machine in FIGURES 1 and 2 of the drawing are for illustrative purposes only.

I claim:

The ornamental design for a vacuum and blower unit for cleaning a textile machine, substantially as shown and described.
